UNITED STATES PATENT OFFICE.

MAX DÉRI, OF VIENNA, AUSTRIA-HUNGARY.

COMBINED ALTERNATING AND CONTINUOUS CURRENT SYSTEM OF DISTRIBUTION.

SPECIFICATION forming part of Letters Patent No. 630,491, dated August 8, 1899.

Application filed July 27, 1898. Serial No. 687,025. (No model.)

To all whom it may concern:

Be it known that I, MAX DÉRI, a subject of the Emperor of Austria-Hungary, residing at Vienna, in the Province of Lower Austria, in 5 the Empire of Austria-Hungary, have invented certain new and useful Improvements in Electrical Distribution; and I do hereby declare the following to be a full, clear, and exact description of the invention.

10 The distribution of electrical energy by means of alternating currents, especially by means of monophase alternating currents, is accompanied by considerable disadvantage for many purposes in spite of the great superiority in economy of leads and of the ease with which the distribution can be regulated. Accumulators cannot be charged with alternating current nor can electrolysis be effected by them, and in starting electromotors difficulties have to be overcome.

15 By this invention the system of distribution combines in a simple manner both kinds of current in a two-wire or three-wire system and renders possible the simultaneous use of 20 the advantages of both kinds of current.

25 In the accompanying drawings, Figure 1 is a diagram illustrating the combination of transformer with a continuous-current generator. Fig. 2 is a similar diagram showing a 30 storage battery as the generator. Figs. 3 and 4 are graphic representations of the currents obtained. Figs. 5 and 6 are diagrams illustrating the application of my invention to polyphase alternating-current systems. Fig. 35 7 is a diagram of an installation according to my system, and Fig. 8 is a diagram of an electric traction system according to my invention.

40 From the central station an alternating current is sent out through the primary leads or conductors. The secondary stations comprise alternating-current transformers and secondary generators of continuous current, such as accumulators or transformers for converting alternating current into continuous current. The secondary generators for alternating current and for continuous currents are arranged in series or connected together.

45 Fig. 1 of the accompanying drawings is a 50 diagram of the combination of a transformer with a continuous-current generator, and Fig. 2 is a diagram of a transformer with an accu-

mulator-battery. In both cases the secondary coil of the transformer and the continuous-current generator are connected up in series. The terminal of the alternate-current coil is designated by 1, that of the continuous-current generator is designated by 3, and the terminal by which the two generators are united (the connecting-point) is designated 60 by 2. The leads or conductors connected with these terminals are lettered L', L², and L³, which last is required only where the connecting combination is used. Between the leads L' and L² there is an alternating pressure, between L² and L³ a continuous pressure, and between L' and L³ a periodically-undulating pressure, (wave-pressure,) consisting of the sum of the two other pressures. In Fig. 3 the characters of the several pressures are indicated graphically. It follows 70 that the separate leads will convey currents which, as may be represented in Fig. 4, are in L' periodically alternating, in L³ continuous, and in L² undulatory, (wave-current.) 75

If a circuit with a high degree of self-induction is formed between L' and L³, the current therein will have shallow waves approximating to a continuous current. If the circuit comprises a continuous electromotive 80 force in a contrary direction, such as might be obtained from a battery, the current therein will approximate to an alternating current. Finally, if both self-induction and polarization are present the wave-current will result. 85

In the last-mentioned case the potential difference of the different parts of the circuit may be given the character of the three different pressures, as may be the kind of the resistance. The state of affairs in the circuit 90 between L' and L³ will be as described even if the connecting-conductor L² is omitted.

The manner in which the combination of a continuous current with a polyphase alternating current is made is indicated in Figs. 95 5 and 6. In Fig. 5 the part 1 2 is the transformer-coil of one phase and 2 3 the series circuit formed of the transformer-coil of the other phase and of the continuous-current source. Between 1 and 2 there will be an 100 alternating pressure and between 2 and 3 an undulatory pressure. In Fig. 6 the continuous-current source is in the connecting-conductor, so that there is an undulatory pres-

sure between 1 and 2 as well as between 2 and 3, but in opposite senses, as the diagram shows.

If at different points of a three-wire or two-wire system on the principles described alternating-continuous-current converters are introduced, so that every alternate-current motor and its accompanying continuous-current machine are connected up together in series, and, as shown in Fig. 1, where the terminals 1 and 3 are connected with the leads L' and L^3 and the middle terminal 2 with the connecting-lead L^2 , the motor part of the converter will be driven by an alternating current between 1 and 2, while the continuous-current part will produce a continuous current between 2 and 3. The converter can, however, receive current in both parts simultaneously, and thus operate as an alternating and continuous current motor combined. A number of converters arranged in this way can maintain in the leads a continuous pressure besides furnishing motive power, and if in addition accumulator-batteries are introduced between L^2 and L^3 at suitable positions these can be charged and discharged, and thus, as buffer-batteries, regulate the pressure and equalize the output of energy. By a system of leads in which a large number of electromotors are driven alternating and continuous currents can be distributed according to the foregoing combination if electromotors combined in the manner of converters are used and buffer-batteries are applied for equalization.

In Fig. 7 is shown a diagrammatic view of a current-distributing installation in accordance with this invention. From the central station C the primary alternating-current leads pass to the interposed transformers T. The secondary stations are arranged as follows: at I, two transformers T T and a battery B; at II, a transformer T and a continuous-current generator G^c , driven by primary current, and at III a transformer T and a battery B. The secondary circuit is formed partly with three wires for different kinds of current, and partly with two wires for continuous current, and partly with two wires for the wave-current. On the three-wire circuit is a consumer's installation at D^5 , consisting of an alternating-continuous-current motor or alternating-continuous-current converter M^a and M^c . The alternating-current motor M^a and the continuous-current motor or generator M^c are mounted upon a common axis, as usual. The continuous-current two-wire circuit supplies a battery B at D' , an electrolytic cell P at D^2 , an arc-lamp A at D^3 , and a continuous-current motor M^c at D^4 . On the wave-current two-wire circuit are arc-lamps in series A A at D^6 , an alternating-continuous-current motor or converter M^a M^c at D^7 , a resistance R in series with a self-induction S for obtaining continuous current at D^8 , and at D^9 a battery B in series with a self-induc-

tion S for obtaining alternating pressure between 1 and 2 and continuous pressure between 2 and 3.

The distribution of current according to this system is particularly appropriate for electric traction, which may, for example, be effected according to the following arrangement, (illustrated in the diagram, Fig. 8): Along the railway-track are laid three leads L' , L^2 , and L^3 . The leads L' and L^2 are connected with transformers and conduct alternating current to the car-driving mechanism. At certain points accumulators are connected with the leads L^2 and L^3 . One of the leads can be constituted by the rail and the earth. The motor of the car consists of an alternating and continuous current motor or an alternating-continuous-current converter, such as indicated at D^5 , Fig. 7. In this combined mechanism the alternating-current armature and the continuous-current armature are connected in series. By switches the alternating-current motors on L' and L^2 and the continuous-current armatures on L^2 and L^3 are put in circuit. The motor mechanism is put in motion at starting by the continuous current; but after a certain degree of speed it is driven chiefly by the alternating current.

The continuous-current motors of the motor mechanism are connected with each other and with the batteries in parallel circuit by the leads L^2 and L^3 , so that there is in these leads a certain driving-pressure, by means of which one part of the motor mechanism yields a continuous current during the journey and, if necessary, also when the car is stopped to another motor—for instance, of a car which is starting or traveling up an incline. In the same way buffer-batteries receive and deliver continuous current and effect an equalization of the output of work from the separate trains. The leads L' and L^3 can also be divided into several sections. To a certain extent also one or other of these contact-leads can be omitted. For example, in stations, where the train travels by the power of the continuous current, the alternating-current contact-lead may be omitted, while in the open track, where the alternating current chiefly is used, the continuous-current contact-conductor may be eliminated.

Under the previously-mentioned conditions the middle common lead L^2 may be to some extent or entirely omitted. There will then be a wave-pressure between the two contact-leads, which, on the one hand, is fed through the transformers and batteries connected in series and with which, on the other hand, the combination car-motors connected in series will be in circuit.

In this system the traveling motor mechanism itself effects the conversion of the alternating current into continuous current; but under certain conditions it may be useful to employ separate stationary converters, or when the central station is in an appropriate

position continuous-current generators in addition to the general continuous-current supply may be used.

The accumulators are as a rule stationary; 5 but buffer-batteries connected in parallel circuit or for special purposes batteries otherwise connected may be also carried with the train.

Starting from the arrangement shown in 10 Figs. 5 and 6, traction installations can be supplied with polyphase alternating currents combined with continuous currents without using more than three contact-leads, (one of them, if necessary, a rail as a return-lead,) 15 which may be connected with the different current sources either as in Fig. 5 or in Fig. 6, and using combined motors in the train driven simultaneously from both current sources, or it may be alternately from one or the other 20 source.

Fig. 8 is a diagram showing, by way of example, the current distribution for traction with three leads as a combination of monophase alternating current with continuous current. C is an alternating-current generator, L L are the primary alternating-current leads, T are transformers, and B are accumulators. The secondary leads—in this case the contact-leads L' L² L³—conduct alternating 25 current, continuous current, and wave-current. The secondary station II comprises a transformer, and secondary station III comprises an accumulator, while I and IV comprise both transformers and accumulators. In 30 each of the last two stations the secondary coil of the transformer and the battery are connected with each other, and the terminals 1 and 2 of the transformer and the terminals 2 and 3 of the battery are connected with the rail-leads L', L², and L³, those terminals and leads 35 being connected which bear the same number. F' and F² are railway cars or trains the contacts of which are in connection with the three leads. On F' there is an alternating-current 40 motor M^a on one axis and a continuous-current motor M^c on the other axis. On one of the axes at F² the two are combined in one machine—a rotary converter M^{rc}. The manner in which by this arrangement the combined motor-mechanism functions, now as a 45 double motor, now as a converter, and in which the pulsating battery equalizes the output of work, will be easily understood from the foregoing explanation.

50 The applications of this combined current-distributing system are not exhausted by the foregoing description and diagrams. There are still possible numerous variations in application to the different forms of electric 55 transmission of power, particularly for purposes of traction.

I claim as my invention—

1. In an electrical distribution system, the combination of alternating-current transformers with continuous-current secondary 65 generators connected in series and three leads therefrom, of which the electromotive force is added together in such a way that between two leads of the series a pressure giving rise to wave-currents is produced, while between 70 the one external lead and the connecting-lead an alternating pressure and between the other external lead and the connecting-lead a continuous pressure is produced, substantially as described. 75

2. An electrical distribution system, comprising a central station with alternating-current generator, and secondary stations receiving alternating current from the central station, said secondary stations having combined 80 in series alternating-current transformers and continuous-current secondary generators, and three leads therefrom, substantially as described, whereby either a wave-pressure, alternating pressure or continuous pressure 85 may be obtained, according to the said leads connected, substantially as described.

3. An electrical distribution system for electric traction, comprising a central station with alternating-current generator and secondary stations receiving alternating current from the central station, said secondary stations having alternating-current transformers and continuous-current generators with three leads or conductors therefrom, in combination with cars having alternating-current motors and continuous-current machines or converters and contacts for the conductors or leads, whereby the motor mechanism on the cars may be driven either by alternating or 100 continuous current or both or being driven by alternating current can deliver continuous current to the conductors or leads, substantially as described. 95

4. An electric distribution system, comprising a central station with alternating-current generator and secondary stations receiving alternating current from the central station, with three leads from the secondary stations, some of which have combined transformers 110 and direct-current generators connected up to the three leads, while others of the secondary stations have transformers only, connected to two of the said secondary leads, substantially as described. 115

In testimony that I claim the foregoing as my invention I have signed my name in presence of two subscribing witnesses.

MAX DÉRI.
